DESIGN FOR A DRAWER PULL

Raymond H. Martin, Bridgeport, Conn., assignor
to The Bassick Company, Bridgeport, Conn., a
corporation of Connecticut

Application November 20, 1935, Serial No. 59,670

Term of patent 3½ years

To all whom it may concern:

Be it known that I, Raymond H. Martin, a citizen of the United States, residing in Bridgeport, in the county of Fairfield and State of Connecticut, having invented a new, original, and ornamental Design for a Drawer Pull, of which the following is a specification, reference being had to the accompanying drawing, forming part thereof.

In the drawing:

Fig. 1 is a front elevation of a drawer pull, showing my new design.

Fig. 2 is a top plan view.

Fig. 3 is an end elevation.

I claim:—

The ornamental design for a drawer pull, as shown.

Signed at Bridgeport, in the county of Fairfield and State of Connecticut, this 15th day of November, 1935.

RAYMOND H. MARTIN.
